SAFETY REVERSIBLE WINDOW

Louis I. Alperin, Scranton, Pa.

Application August 8, 1941, Serial No. 406,063

4 Claims.

(Cl. 20—49)

My invention relates broadly to windows and more particularly to an arrangement of double-hung, slideable and reversible window sash construction and hardware for converting existing double-hung window sashes into a reversible sash arrangement.

One of the objects of my invention is to provide a simplified arrangement of hardware which may be applied to existing double-hung window sash installations to enable such sashes to be operated either in vertically slideable arrangement or in tilting and reversing arrangement.

Another object of my invention is to provide a construction of double-hung reversible window sash arrangement having projectible and retractible weather-stripping at opposite sides of each sash for excluding entry of air and moisture.

Still another object of my invention is to provide a construction of double-hung reversible window sash in which the sashes may be tilted to restrained and controlled angular positions from a normal vertical plane.

A further object of my invention is to provide a construction of hardware for both the upper and lower sashes of a double-hung window for controlling the projection and retraction of weather-stripping for thus freeing the window sash preparatory to tilting or angular movement thereof.

A still further object of my invention is to provide a construction of sliding lock for application to double-hung window sashes having means for effectively obstructing the entry of air and moisture adjacent the sash and compositely locking the sash for movement in vertical planes.

Another object of my invention is to provide a construction of a sliding lock for the sash of a double-hung window having means within the lock and coacting with the sash for controlling the angular movement of the sash to selected angular positions.

Still another object of my invention is to provide a sliding lock for double-hung window sashes which includes pawl and ratchet mechanism housed within the sliding lock for restraining the tilting movement of the sash to selected angular positions.

A further object of my invention is to provide a construction of sliding lock for double-hung reversible window sashes in which the structural members forming the sliding lock are so spaced and slotted that a portion of the assembled elements thereof provide securing means for the

sash-cords for controlling the vertical sliding movement of the sashes.

Other and further objects of my invention reside in the construction of hardware for reversible double-hung window sashes as set forth more fully in the specification hereinafter following by reference to the accompanying drawings, in which:

Figure 1 is a front elevational view of the safety reversible window of my invention with parts broken away and shown in section; Fig. 2 is a vertical transverse sectional view taken on line 2—2 of Fig. 1 and shows more particularly the arrangement of the sashes with respect to the casing and showing in dotted lines the two sashes in a tilting position; Fig. 3 is a fragmentary longitudinal sectional view showing a portion of the lower sash and more particularly the left stile of the window together with the sliding lock; Fig. 4 is a similar view showing the sliding lock in section and more particularly the weather-stripping member projecting within the sliding lock and the sash consequently locked against tilting movement; Fig. 5 is a view similar to Fig. 4 but showing the weather-stripping member retracted and the sash prepared for tilting; Fig. 6 is a face view of the lower sash showing the retractible and projectible weather-stripping member; Fig. 7 is a horizontal sectional view on an enlarged scale taken substantially on line 7—7 of Fig. 4 and showing the mortise in the edge of the sash in which the weather-stripping member moves; Fig. 8 is a horizontal sectional view taken on line 8—8 of Fig. 4 and showing more particularly a portion of the operating knob for projecting the sliding lock with respect to the lower sash against the action of a flat leaf spring; Fig. 9 is a horizontal sectional view taken on line 9—9 of Fig. 4; Fig. 10 is a transverse vertical sectional view taken substantially on line 10—10 of Fig. 4 and showing more particularly the ratchet wheel and associated pawls and spring members by which relatively deep notches in the ratchet wheel may be engaged and the sashes maintained in position to permit the sashes to slide freely up and down; Fig. 11 is a sectional view taken substantially on line 11—11 of Fig. 4 and shows more particularly a portion of the sliding lock for the lower sash; Fig. 12 is a sectional view taken on line 12—12 of Fig. 3 showing the operating knob and associated parts and illustrating the flat leaf spring for actuating the weather-stripping member; Fig. 13 is a sectional view showing the sash tilted at right angles to its normal position and showing how the pawls

of the flat springs engage the shallow notches on the periphery of the ratchet wheel and consequently restrain the sash against uncontrolled movement; Fig. 14 is a sectional view taken substantially on line 14—14 of Fig. 8 and showing more particularly the deep and shallow notches on the periphery of the ratchet wheel and also illustrating the engagement of the pawls on the flat locking springs with the ratchet wheel; Fig. 15 is a sectional view through a portion of the sash showing it tilted in full lines and wherein it is shown that the pawls on the flat springs now engage the shallow notches on the periphery of the ratchet wheel and force the flat springs against their abutment faces in the sliding lock and restrain the sash against uncontrolled movement; Fig. 16 is an elevational view of the hardware applied to the upper sash with a flush mounting lever control to allow the upper and lower sashes to readily pass each other; Fig. 17 is a fragmentary longitudinal sectional view showing one limiting position of the leaf spring which controls the weather-stripping in the upper sash of the double hung window; Fig. 18 is a view similar to the view illustrated in Fig. 17 but showing the control mechanism for the leaf spring shifted to the opposite limiting position; Fig. 19 is a transverse sectional view taken on line 19—19 of Fig. 16; Fig. 20 is an elevational view of the upper sash of the double-hung window showing a modified arrangement of control means for the weather-stripping member in the upper sash with parts broken away and illustrated in section; Fig. 21 is a fragmentary view partially in front elevation and partially in vertical section showing the control means for the weather-stripping member in the upper sash as illustrated in Fig. 20; Fig. 22 is a vertical sectional view through a portion of the upper sash and illustrating in section the control means moved to a position which interlocks the weather-stripping member with the sliding lock; Fig. 23 shows the control means of Figs. 20—22 shifted to a position which enables the spring means within the mortised sash to retract the weather-stripping member from the sliding lock; Fig. 24 is a side elevational view of the upper sash of Figs. 20—23; Fig. 25 is a fragmentary front elevational view of the upper sash frame illustrating the arrangement of the projecting and retracting means for the weather-stripping member within the sash frame; Fig. 26 is a transverse sectional view on line 26—26 of Fig. 24; Fig. 27 is a fragmentary vertical sectional view through the frame of the upper sash on line 27—27 of Fig. 26; Fig. 28 is a perspective view of the mounting plate forming the journaling means for the actuator of the weather-stripping member in the upper sash illustrated in Figs. 20—27; and Fig. 29 is a perspective view of the cam actuator employed in the structure of the upper sash illustrated in Figs. 20—27.

My invention contemplates the adaptability of present day vertically slidable double-hung window sash to an improved reversible and tilttable arrangement whereby each of the sashes may be reversed or tilted to a position for facilitating cleaning. This is particularly desirable for windows located at relatively high elevations, as both sides of the window may then be readily cleaned from the inside of the building structure. While adapting the vertically slidable window sashes to a tilting or reversible position, I also obtain a number of additional advantages such as the preventing of rattling of the sash and the

prevention of direct passage of air, moisture, dust or foreign matter by effective weather-stripping between the reversible or tilttable sash and a slidable locking slide which is slidable within the window frame. That is to say, the combination structure of my invention provides an arrangement not heretofore obtainable in a reversible or tilttable sash structure, for by the coaction of parts in the assembly of my invention, I provide for reversible or tilttable movement of the sash; a substantial weather proofed locking of the sash; the maintenance of the sash against rattling, and above all, I provide a mechanical assembly of very substantial strength for resisting abnormal forces which may be directed against the sash. An actuator at each side of the shaft must be released before the sash may be tilted or reversed so that accidental falls through the sash are substantially prevented.

My invention contemplates the adaptation of the hardware embodying the features of my invention both to double-hung slidable sash already installed as well as to new installations of sash. That is to say, the hardware embodying the features of my invention may be incorporated into the sash as manufactured, or by very simple changes, existing sashes may be adapted to use the features of my invention.

Where my invention is applied to existing double-hung sashes, it is only necessary to remove the upper and lower sashes from the window frame and cut down the sash at each side approximately three-fourths of an inch. A narrow slot or groove is then mortised into the edge of the sash and an actuator mounted in the frame of the sash for controlling the yieldable combination lock and weather-stripping member which may be spring mounted in the mortised slot or groove in the sides of the sash frame.

The hardware fitting which controls the ejection and retraction of the weather-stripping member also provides a recess for receiving the controlled pivot member extending from the sliding lock. By the coaction of the controlled pivot member, the sliding lock is movable under control of ratchet members to selected step by step positions, and in each such position is secured with substantial rigidity thereby preventing uncontrolled tilting movement of the sash. The sliding lock is of a thickness which compensates for the material removed from the sides of the sash thereby enabling the sash to be reinstalled in the stiles of the window frame with the composite fittings of my invention applied thereto. The sliding lock includes longitudinally extending grooves which coact with the projectible and retractible weather-stripping member carried by the sash. The sliding lock has a length corresponding with the height of the sash and slides vertically in the stiles of the window frame by reason of the interlocking relation between the controlled pivot member and the hardware fitting carried by the sash and also by reason of the interlock formed between the weather-stripping member and the longitudinally extending grooves in the sliding lock. So long as it is desired to restrain the window sash against tilting movement, the weather-stripping member is maintained by movement of the actuator in engagement with the longitudinally extending grooves in the sliding lock. This interlocking relation not only prevents unauthorized entry through the window from the outside, but also insures a relatively tight weather seal at each side of the sash. Moreover, the abutment between opposite faces

of the weather-stripping member and the longitudinally extending grooves insures against accidental yielding of the sash should abnormal pressure be forced against the sash. Even when the weather-stripping member is retracted, the sash is prevented from unrestrained or uncontrolled tilting movement by operation of the ratchet mechanism associated with the controlled pivot member carried by the sliding lock.

The upper and lower sashes of the double-hung sash system may be vertically adjusted to any selected position, the weather-stripping device retracted in a selected sash and then that sash tilted to the selected position. The sash may be entirely reversed in order to render accessible from the interior either side of the window for convenience in cleaning the window from the inside of the building structure. Such reversing movement is at all times controlled and restrained by operation of the ratchet associated with the controlled pivot member.

The hardware of my invention is extremely simple in its manufacture and production, and embodies numerous novel features among which I mention the cut-away portion of the upper end of the sliding lock which immediately engages the stile of the window frame for permitting clearance of the sash weight rope guide pulleys housed in the window frame, and also the provision for passage of the sash weight rope without obstruction. The fact that only two simple coacting hardware members are required as fittings at each side of the sash to accomplish the conversion of an ordinary vertically slideable sash into a convenient reversible or tilttable anti-rattling, lockable weather protected installation renders the hardware of my invention applicable to the broad field of double-hung window installations for converting such window into the modern rear and tilting arrangement herein described. However, my invention is applicable to window sash construction on a quantity production basis as initially supplied by the factory either in the wood-sash construction or in metal-sash construction, in which sash construction the factory assembly embodies the initial installation of the weather-stripping member and actuator at each side of the sash and the furnishing of a sliding lock which is disposed intermediate the stiles of the window frame and the sash. Where the principles of my invention are embodied in metal sash, the weather-stripping device is yieldably mounted in reyectible and retractible arrangement in the opposite edges of the sash and operated by the controllable actuator. A central recess is formed in the hardware for receiving the controlled pivot member which projects from the sliding lock which is provided intermediate the metal stiles of the metallic window frame and the metal frame of the window sash. Longitudinally extending slots in the sliding lock coact with the reyectible and retractible weather-stripping device providing the same advantages heretofore explained in connection with the installation of the hardware of my invention in wood-sash construction. Inasmuch as the principles of my invention are the same whether applied to wood or metal sash, my invention will be described in detail more particularly in association with wood-sash installations and thereafter described more generally in connection with metal-sash installations.

Referring to the drawings in more detail reference character 1 designates the frame of a double-hung window containing the longitudinally

extending stiles 2 and 3 in which the sliding locks carried by opposite edges of the lower sash 4 and upper sash 5 are slideable. The opposite extreme edges of the sashes are cut down in width to receive the sliding locks, the width of which compensates for the material removed from the sides of the sash, thereby enabling the sash to be slidably adjustable within the longitudinally extending stiles of the window-frame. The upper sash 5 is illustrated as having sliding locks 6 and 7 applied to the opposite edges thereof. The lower sash 4 has the sliding locks 8 and 9 applied to opposite edges thereof. In each instance the thickness of the sliding locks is such that the sashes fit the longitudinally extending stiles in the same manner that the sashes as originally constructed would fit within the stiles.

The sashes are each mortised in their opposite edges as I have represented in the case of the lower sash 4 at 10. This mortise terminates short of the top and bottom edges of the sash so that there is no exposure for the entry of air or moisture through the window-frame. The mortise provides a housing for receiving the weather-stripping member 11 which is transversely projectible and retractible with respect to the side of the sash. The rear edge of the weather-stripping member 11 carries loop members 12 and 14 through which the opposite ends of longitudinally extending leaf spring 15 slidably extend. The leaf spring 15 is normally substantially straight or longitudinal, as represented in Fig. 5, and in a position shown in Fig. 5, tends to draw the weather-stripping member 11 inwardly. In order to project weather-stripping member 11, I provide centrally of the opposite sides of the frame of the sash, a tumbler or cam member 16, which is actuated by rotatable shaft 17, which projects through escutcheon plate 18 and is actuated by control knob 19 secured to the end thereof. To provide mounting means for the tumbler or cam member 16, I drill the sash 4 as represented at 20 for the passage of the cylindrical portion 21 of the tumbler or cam member 16. Thus by grasping the control knob 19 the tumbler or cam member 16 may be rotated through an angular distance of approximately 180° to eject the weather-stripping member 11 against the influence of spring 15 or to release the weather-stripping member 11 to enable weather-stripping member 11 to be drawn inwardly into the mortise 10 as illustrated in Fig. 5. The escutcheon plate 18 connects with a face plate 22 which is provided with a reenforced central sleeve-like aperture 23 which forms a journal for the pivot bar 24 of the sliding lock 8. The weather-stripping member 11 is centrally recessed at 25 to permit ejection of the weather-stripping member 11 into locking position in the slot 26 in sliding lock 8. The slot 26 extends longitudinally of the sliding lock 8 on either side of the center thereof represented at 27. The central portion 27 of the sliding lock 8 provides a mounting means for the pivot bar 24. The pivot bar 24 contains a square hub portion 28 which is rotatably mounted by means of screw 29 on the external side plate 30 of the sliding lock 8. The square hub 28 reduces in section to a square shank or terminus 31 that extends into the reenforced sleeve-like aperture 23 of the plate 22. The square shank 31 passes through aperture 32 in the internal plate 33 of the sliding lock 8 and is free to revolve because of the fact that the chamfered head of screw 29 which passes through the correspondingly apertured and

chamfered plate 30 is screwed home to the limit of the screw threaded recess in the square hub 28, allowing sufficient clearance to permit rotation of the square shank 31. In order to control and restrict the rotation of square shank 31, I provide a deformed ratchet wheel 34 having a square aperture 35 therethrough to permit the ratchet wheel to be inserted over the square hub 28 and turn with the hub. The ratchet wheel 34 is provided with ratchet teeth 36 and in diametrically opposite positions is provided with relatively deep notches 37 and 38 for maintaining the sash in the position for normal vertical sliding movement. In order to insure against accidental opening of the sash by movement about the central pivots I provide two ratchet engaging pawls represented at 39 and 40 carried by resilient strip members 41 and 42. The resilient strip members 41 and 42 extend substantially the entire length of the sliding lock 8. Each of the strip members have their ends turned inwardly and engaged around the members which form the spacing means for the plate members 30 and 33. The spacer members comprise sleeves 43 and 44 through which screws 45 and 46 extend. Screws 45 and 46 have headed ends which pass through external plate 30 of the sliding lock 8 and engage in screw threaded apertures in the internal plate 33 of sliding lock 8. The ends of the resilient strip members 41 and 42 are substantially hook-shaped as represented at 45a and 46a and engage around the sleeves 43 and 44. The resilient strip members 41 and 42 are assembled in engaged position with respect to the sleeves 43 and 44 before the internal plate 33 is mounted in position. When the internal plate 33 is mounted in position the sliding lock 8 is completed as a unit and coacts with the sash in both the vertically sliding and angularly adjustable positions thereof.

In order to lighten the structure of the sliding lock 8 I provide longitudinally extending slots 26a in the external plate 30 in alignment with the slots 26 in internal plate 33. The upper end of external plate 33 has the slot 26a thereof enlarged as represented at 26b to facilitate the assembly of the sash when forcing into position the knotted end 47 of the sash-cord 48. The spacer sleeves 43 and 44 which are secured in position intermediate the external plate 30 and the internal plate 33 of the sliding lock 8 are so spaced that the knotted end at the sash-cord 48 shown at 47 cannot pass through the space between the hook shaped ends 45a and 46a of the resilient strip members 41 and 42. Accordingly the slotted end portion of external plate 30 provides a quick operative opening through which the knotted end of the sash may be introduced and secured in position. This arrangement facilitates installation and materially reduces time necessary for assembly. The ends of the sash-cords 48 operate on pulleys 50 and are connected at the ends to sash weights 51 which are operative as usual in the wells 52 of the window casing.

In order to permit the mutual passage of the sashes 4 and 5 in sliding vertical arrangement the control for the leaf spring 15 is arranged flush with the frame of the upper sash 5. The hardware supporting the flush type of control device is represented as including plate member 53 fastened mid-way of the vertical height of the upper sash 5 and providing a journaling means for a control lever 54 which is pivotally mounted with respect to the sash. By moving control lever 54 from one extreme position flush with the sash to

an opposite extreme position flush with the sash, the position of the ejecting device for the weather-stripping member 11 is controlled. The escutcheon plate of the hardware 53 contains 5 finger recesses 55 and 56 into which the control lever 54 is adapted to move to a position flush with the escutcheon plate in a position to either 10 release or lock the sash with respect to the sliding lock in Figs. 1 and 2. I have shown the upper sash 5 mortised at 60 to receive weather-stripping member 61 which is normally withdrawn inwardly by the action of leaf spring 62 secured at its opposite ends at 63 to the weather-stripping member 61. The control lever 54 which is journaled by any suitable means 64 in escutcheon 15 plate 53 projects rearwardly as indicated at 65 and engages a diagonally extending slot 66 in a cam block 67. Vertical movement of the control lever 54 shifts the cam block 67 in a transverse 20 direction. In the position illustrated in Fig. 17 the weather-strip member 61 is projected against the restraint of leaf spring 62. In the position illustrated in Fig. 18 the weather-stripping member 61 is allowed to retract under the pressure 25 produced by the tendency of leaf spring 62 to straighten within mortise 60. In the position illustrated in Fig. 17, weather-stripping member 61 is engaged in the longitudinal groove of the sliding lock. In the position shown in Fig. 18 30 the weather-stripping member 61 is retracted from the groove in the sliding lock.

I may provide a modified form of control means for the weather-stripping member in the upper sash as illustrated in Figs. 20-29. In this modified form of my invention the upper sash is recessed at 68 to receive the mounting plate 69 which carries a projection 70 thereon which extends into the mortise 60 of the upper sash 5. The projection 70 carries a limiting stop pin 71 which forms one of the abutments limiting the movement of cam 72 which is carried by shaft 73 journaled in the projection 70 of plate 69. The end of shaft 73 is flattened as represented at 74 and provides means for pivotally connecting the hinged key 75. The hinged key 75 normally hangs in a position in which the key is wholly flush with the face of the sash so that the upper and lower sash may readily pass each other in the stiles. However the key 75 may be readily grasped and moved outwardly and serve as a means for turning the cam 72. In the position illustrated in Fig. 22 the cam 72 is moved to a position projecting weather-stripping member 61 against the action of leaf spring 22, while in Fig. 23 the cam 72 is shown moved to a position in which leaf spring 62 retracts weather-stripping member 61, thus freeing the sash 5 from engagement with the locking slide and permitting the sash to swing about pivot bar 24 as a center. Facing hardware 76 is provided on the upper sash 5 with the square recess 77 therein for receiving the end of the pivot bar 24. Step by step pawl and ratchet mechanism indicated generally at 34 is provided in the sliding lock for the upper sash 65 in a manner similar to the explanation heretofore given for the lower sash construction. Thus the upper sash is shiftable to various angular positions and restrained in a selected position.

The sash is arranged in the stiles in such manner that the sliding lock is wholly covered by framing strips 57, 58 and 59, thereby effectively obstructing the entry of air or moisture. When weather-stripping member 11 is projected the entry of air or moisture is further obstructed at 75 the same time that the sash is locked against

turning. The weather-stripping member 11 serves not only to exclude air and moisture but also serves to confine the sash to vertical movement in the stiles. When, however, it is desired to angularly tilt or reverse the position of either the upper or lower sash, the control actuators 54 in the case of the upper sash 5 and the control actuators 19 in the case of the lower sash 4 are operated to remove the rear abutments from the weather-stripping members 11, thereby enabling leaf springs 15 to restrict the weather-stripping 11 to a position in which the weather-stripping 11 is withdrawn from and is clear of the slots 26 in the plate 33 of the sliding lock 8. Under these conditions the sash is free to be angularly tilted as represented in Figs. 2, 13 and 15 or to be completely reversed for cleaning either side of the glass from the inside of the building. The ratchet teeth 36 on ratchet 34 engage the pawls 39 and 40 on strips 41 and 42 of sliding lock 8 and prevent unrestrained tilting movement of the sash so that under conditions where substantial pressure may be placed against the sash the sash is restrained from unlimited and uncontrolled movement. The relatively deep notches 37 and 38 disposed in diametrically opposite positions of the ratchet 34 normally maintain the sash in a vertical position instantly ready for tilting movement or reversing movement when the weather-stripping 11 is withdrawn from engagement with slots 26 of sliding lock 8.

The construction of my invention provides a composite arrangement of sliding and swinging sash employing retractible and rejectible weather-stripping which serves in addition to its weather-stripping function as means for preventing tilting or reversing movement of the sash when the sash is to be used in its normal vertically slideable relationship.

I have illustrated my invention in association with frame or wood sash construction but it is to be understood that the principles of my invention are equally applicable to metallic sash construction. Moreover I have illustrated my invention in a form in which the window construction is completed by factory production. It will be understood, however, that the hardware of my invention is applicable to custom-built jobs and to the conversion of existing double-hung sashes.

I have found the construction illustrated herein highly practical and efficient in operation and while I have illustrated my invention in its preferred embodiment, I realize that changes may be made in the shape, size and construction of the hardware and component parts shown herein and I desire that it be understood that I intend no limitations upon my invention other than may be imposed by the scope of the appended claims.

What I claim as new and desire to secure by Letters Patent of the United States is as follows:

1. A sliding bar for guiding a double hung window sash in longitudinally extending stiles in a window frame for composite translatory and angular movement of the sash with respect to the window frame comprising a pair of strip members symmetrically bifurcated at each end thereof for the projection and retracting of a weather-stripping member therethrough from the sash, spacer members disposed between the ends of said strip members, securing means passing through said spacer members for uniting said strip members in spaced relation, a pivot bar disposed in the central portion of said strip members and pro-

jecting therefrom for pivotally engaging the window sash, and means supported between said spacer members for controlling the angular movement of said pivot bar.

5 2. A sliding bar for guiding a double hung window sash in longitudinally extending stiles in a window frame for composite translatory and angular movement of the sash with respect to the window frame comprising a pair of strip members symmetrically bifurcated at each end thereof for the projection and retracting of a weather-stripping member therethrough from the sash, spacer members disposed between the ends of said strip members, securing means passing through said spacer members for uniting said strip members in spaced relation, a pivot bar disposed in the central portion of said strip members and projecting therefrom for pivotally engaging the window sash, and a ratchet member carried by said pivot bar intermediate said strip members, resilient strip members extending longitudinally between said first mentioned pair of strip members and supported at opposite ends thereof by said spacer members and pawls carried by said resilient strip members and engaging said ratchet for controlling the angular movement of said pivot bar.

10 3. A sliding bar for guiding a double hung window sash in longitudinally extending stiles in a window frame for composite translatory and angular movement of the sash with respect to the window frame comprising a pair of strip members symmetrically bifurcated at each end thereof for the projection and retracting of a weather-stripping member therethrough from the sash, spacer members disposed between the ends of said strip members, securing means passing through said spacer members for uniting said strip members in spaced relation, a pivot bar disposed in the central portion of said strip members and projecting therefrom for pivotally engaging the window sash, a ratchet member carried by said pivot bar intermediate said strip members, resilient strip members extending longitudinally between said first mentioned pair of strip members and supported at opposite ends thereof by said spacer members and pawls carried by said resilient strip members and engaging

15 40 said ratchet for controlling the angular movement of said pivot bar, said ratchet member including ratchet teeth and a pair of diametrically disposed relatively deep notches therein engageable by said pawls for maintaining said pivot bar in a position of engagement with said sash for normal vertical sliding movement thereof in the stiles of the window frame or selectively maintaining said sash in an angular position with said pawls correspondingly engaging the teeth in said ratchet.

45 5. A sliding bar for guiding a double hung window sash in longitudinally extending stiles in a window frame for composite translatory and angular movement of the sash with respect to the window frame comprising a pair of strip members, spacer members disposed between the ends of said strip members, securing means passing through said spacer members for uniting said strip members in spaced relation, a pivot bar disposed in the central portion of said strip members and projecting therefrom for pivotally engaging the window sash, and resilient means supported between said spacer members for controlling the angular movement of said pivot bar.

60 6. A sliding bar for guiding a double hung window sash in longitudinally extending stiles in a window frame for composite translatory and angular movement of the sash with respect to the window frame comprising a pair of strip members, spacer members disposed between the ends of said strip members, securing means passing through said spacer members for uniting said strip members in spaced relation, a pivot bar disposed in the central portion of said strip members and projecting therefrom for pivotally engaging the window sash, and resilient means supported between said spacer members for controlling the angular movement of said pivot bar.

LOUIS I. ALPERIN.
